No. 36,400.

Patented June 30, 1903.

UNITED STATES PATENT OFFICE.

ROBERT K. STORY, OF BROOKLYN, NEW YORK.

DESIGN FOR A RADIATOR-SECTION.

SPECIFICATION forming part of Design No. 36,400, dated June 30, 1903.

Application filed March 28, 1903. Serial No. 150,069. Term of patent 7 years.

To all whom it may concern:

Be it known that I, ROBERT K. STORY, a citizen of the United States, and a resident of the borough of Brooklyn, in the county of Kings and State of New York, have invented a certain new, original, and ornamental Design for Radiator-Sections, of which the following is a specification.

The design is shown in the accompanying drawing, which is a view in elevation of the front face of a radiator-section.

What I claim as new is—

The ornamental design for a radiator-section as shown.

Signed at New York, in the county of New York and State of New York, this 16th day of March, A. D. 1903.

ROBERT K. STORY.
